US00D842314S

(12) **United States Design Patent** (10) Patent No.: US D842,314 S
Govindan Sankar Selvan et al. (45) Date of Patent: ** Mar. 5, 2019

**(54) DISPLAY SCREEN OR PORTION THEREOF
WITH GRAPHICAL USER INTERFACE**

(71) Applicant: **SMARTORG, INC.**, San Jose, CA
(US)

(72) Inventors: **Lokmanyathilak Govindan Sankar Selvan**, San Jose, CA (US); **Fan Yu**, Los Altos, CA (US); **Suhui Chen**, Cupertino, CA (US); **Peter Charles McNamee**, Menlo Park, CA (US); **Somik Raha**, San Jose, CA (US); **Jean Yao**, Saratoga, CA (US)

(73) Assignee: **SMARTORG, INC.**, San Jose, CA
(US)

(**) Term: 15 Years

(21) Appl. No.: 29/631,221

Related U.S. Application Data

(62) Division of application No. 29/588,330, filed on Dec. 20, 2016, now Pat. No. Des. 810,100.

CLAIM

The ornamental design for a display screen or portion thereof with graphical user interface, as shown and described.

DESCRIPTION

The FIGURE is a front view of a display screen or portion thereof with graphical user interface showing our new design.

The broken lines in the drawings illustrate a display screen or portion thereof and elements of the graphical user interface that form no part of the claimed design.
